UNITED STATES PATENT OFFICE.

ELDEN I. STAPLES, OF EAST PITTSBURGH, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed November 8, 1924. Serial No. 748,560.

My invention relates to motor control system and it has particular relation to control systems employed to govern the operation of a plurality of motors for actuating a rail-way motor vehicle in mountainous country.

One object of my invention is to provide a system of control for governing a plurality of motors that actuate a motor vehicle or locomotive over railroad track in mountainous country in which the grade of the track is so heavy that rack sections must be provided between the rails of the track to engage one or more gear members mounted upon the vehicle.

15 A second object of my invention is to provide a control system for governing the operation of a plurality of motors whereby the ratio of speed between certain motors may be fixed at a predetermined value.

20 Another object of my invention is to provide a control system for so governing both a group of motors that are employed to drive the wheels of a railway motor vehicle and another group of motors that are employed 25 to drive a gear wheel which engages a rack member that the peripheral speed of the gear wheel and the wheels of the vehicle are substantially equal at the time said gear wheel engages the rack member.

30 Another object of my invention is to provide means for simultaneously governing the speed of the wheels of a motor vehicle and a gear member mounted thereon and adapted to engage a rack member longitudinally 35 mounted between the rails upon which the vehicle operates.

Still another object of my invention is to provide a system of control for a railway motor vehicle whereby a locomotive may be 40 driven upon a portion of the track in which a rack section is located without danger of stripping the teeth of either the rack section or the gear wheel which is mounted upon the locomotive and adapted to engage the rack section.

45 Briefly speaking, my invention comprises providing a control system for governing a plurality of motors for actuating a railway vehicle of which certain of these motors are 50 employed for the normal operation of the vehicle and others of the motors are employed for abnormal operation. These motors that are employed for abnormal operation are driven at a higher speed than those 55 which are employed during normal opera-

tion. The motors employed for abnormal operation actuate a gear wheel which is adapted to engage a rack member which is securely mounted between the rails over which the vehicle travels. The control sys- 60 tem so governs the speed of all the motors that the ratio of speed of the different motors may be so fixed that the peripheral speed of the adhesion wheels and the gear wheel may be made substantially equal at the time 65 the gear wheel engages the rack member.

For a better understanding of my invention, reference may be made to the accompanying drawing Figure 1 of which is a diagrammatic view of a motor control system constructed in accordance with my invention and employed to govern a plurality of motors of a railway motor vehicle which operates through mountainous country.

70 Fig. 2 is a sequence chart showing the sequence of operation of the switches illustrated by Fig. 1 of the drawing.

Figs. 3 to 8, inclusive, are diagrammatic views showing the main control circuits that are illustrated by Fig. 1 of the drawing at 80 different periods during the placing in operation of the motors for abnormal operation during the period said vehicle is passing over a portion of track where the grade is very great.

85 Fig. 9 shows a cross-sectional view of railroad track upon which is mounted a railway motor vehicle constructed in accordance with my invention, only the lower portion of the vehicle being illustrated.

90 Fig. 10 is a longitudinal sectional view of the rack member illustrated in Fig. 9 of the drawing and the gear wheel of the locomotive which engages the rack member.

95 Fig. 11 is a view, in side elevation, of a wheel of a vehicle and a motor mechanically connected thereto.

100 Referring particularly to Fig. 1 of the drawing, a plurality of switches 1 to 17, inclusive, and a plurality of accelerating resistors 18 and 19 are employed to govern the operation of a plurality of dynamo-electric machines or motors 21 to 26, inclusive, in a manner hereinafter more fully described. The motors 21 to 24 inclusive, are employed 105 to drive a motor vehicle, of which they constitute a part, during normal operation of the vehicle and the motors 25 and 26 are employed for abnormal operation of the same vehicle. The motors 21 to 26, inclusive, may 110

be energized in a manner hereinafter more fully described from a source of electrical energy marked "Trolley." The motors 21 to 26, inclusive, are provided with corresponding series field-magnet windings 27 to 32, inclusive, and with corresponding armatures 33 to 38, inclusive. All of the motors 21 to 26, inclusive are designed to be of the same size, shape and to develop the same 10 horse power under like electrical conditions.

The armatures 33 to 36, inclusive, of the motors 21 to 24, inclusive, are mechanically connected to a plurality of wheels 41 by means of axles 42, in the manner illustrated 15 by Fig. 11 of the drawing. The wheels 41 are adapted to roll upon the rails 43 which are securely mounted upon the ties 44 constituting part of the track 45 (see Fig. 9). The wheels 41 have smooth flanges and the 20 tractive effort that may be applied through the wheels 41 is limited by their adhesion to the rails 43.

The tractive force which the motors 21 to 24, inclusive, transmit to the vehicle is limited by the adhesion of the wheels 41 to which they are mechanically connected. The armatures 37 and 38 of the motors 25 and 26, respectively, are mechanically connected to a gear wheel 46 in a manner hereinafter 30 more fully described. The gear wheel 46, which is securely mounted upon an axle 47 of the vehicle, is adapted to engage a rack member 48 which is securely mounted between the rails 43 forming a part of the 35 track 45.

The motors 25 and 26 are each connected to corresponding gear members 49 by means of rotatable shafts 50. The gear members 50 are adapted to engage the gear member 40 51 which is securely mounted upon the rotatable shaft 47. Both the gear wheel 46 and rack member 48 are provided with a plurality of corresponding teeth 52.

The design of the gear wheels 46, 49 and 45 51 is such that the motors 25 and 26 must travel at approximately twice the speed of the motors 21 to 24, inclusive, for the peripheral speed of the gear wheel 46 to be the same as that of the peripheral speed of 50 the vehicle wheels 41.

Referring again particularly to Fig. 1 of the drawing, switches 1 to 5, inclusive, are employed to shunt portions of the resistor 19 and switches 6 to 10, inclusive, are employed to shunt portions of the resistor 18. Switches 12 and 13 are employed to connect the series field-magnet windings 31 and 32 of the motors 25 and 26, respectively, in 55 series relation with the series field-magnet windings 27 to 30 inclusive, and armatures 33 to 36 inclusive of the corresponding motors 21 to 24, inclusive. The parallel-connecting switch 14 is employed to connect the 60 series field-magnet windings 27 to 30, inclusive, in series relation with the armatures 33 to 65

36 inclusive, of the motors 21 to 24 inclusive. The ground switch 15 is employed to connect the series field magnet windings 31 and 32 of the motors 25 and 26 respectively, directly to ground. The line switches 16 and 17 are employed for connecting the group of motors 21 to 24, inclusive, and the group of motors 25 to 26, respectively, to the source of electrical energy marked "Trolley".

The description of the operation of my 75 control system will be confined to the operation of the vehicle just prior to and just after the engagement of the rack wheel 46 with the rack member 48, for this invention is intended to eliminate the difficulties 80 encountered at the time the rack wheel 46 is brought into engagement with the rack member 48.

These difficulties are caused by the shock 85 of engagement of the teeth 52 of the gear wheel 46 meshing with teeth 52 of the rack member 48. This impact is very great because of the relatively great rotary speed of 90 the rack motor armatures 37 and 38, and their considerable mass.

Let us suppose that a railway vehicle constructed in accordance with my invention is approaching a portion of the track that is provided with a rack member 48, when it will then be the duty of the engineer to slow 95 down the speed of the vehicle. The decrease in the speed of the locomotive is effected by first connecting the motors 21 to 24, inclusive, in the manner illustrated by Fig. 3 of the drawing. At this time, the motors 25 and 26 are inoperative. The accelerating 100 switches 1 to 5 inclusive are closed and a circuit is established from the source of electrical energy marked "Trolley" through the line switch 16, accelerating switches 1 to 5, inclusive, armatures 33 to 36, inclusive, of the corresponding motors 21 to 24 inclusive, parallel-connecting switch 14 and series field-magnet windings 27 to 30, inclusive, of the corresponding motors 21 to 24, inclusive, 105 to ground. The speed of the motors 21 to 24, inclusive, is then decreased by consecutively opening the switches 5, 4, and 3 in the order illustrated by steps 2 to 4, inclusive, of the sequence chart of Fig. 2, the circuit corresponding 110 to position 4 of the sequence chart being illustrated in Fig. 4. When the switches 3 to 5, inclusive, have been opened the speed of the motor vehicle will become practically 5 kilometers per hour. It is desirable that the speed of the motor vehicle remain at this rate until after the rack wheel 46 engages the rack member 48.

The next step in the operation of my control system is to so energize the field magnet winding 31 and 32 of the motors 25 and 26, respectively, that their energization shall be the same as the series field-magnet windings 27 to 30, inclusive, of the corresponding 120 motors 21 to 24, inclusive. This is 130

effected by closing the series-connecting switches 12 and 13 as illustrated by step 5 of the sequence chart of Fig. 2 and by Fig. 5 of the drawing.

6 The parallel-connecting switch 14 is then opened, in accordance with position 6 of the sequence chart of Fig. 2, thereby energizing the series field-magnet winding 31 and 32 of the motors 25 and 26 which have been 10 previously connected in series relation with the motors 21 to 24, inclusive. The circuit corresponding to position 6 of the sequence chart is illustrated by Fig. 6 of the drawing.

7 The accelerating switches 1 and 2, the line switch 16, the series connecting switches 12 and 13 are closed, to correspond to position 15 6 of the sequence chart of Fig. 2, thereby establishing a circuit from the trolley through the line switch 16, accelerating contacts or switches 1 and 2, a portion of accelerating resistor 19, armatures 33 to 36, inclusive, of the corresponding motors 21 to 24, inclusive, series connecting switch 12, series field-magnet windings 31 and 32 of 20 the motors 25 and 26, respectively, and series field-magnet windings 27 to 30, inclusive, of the corresponding motors 21 to 24, inclusive, to ground.

8 The next step in effecting the operation 30 of the motors 25 and 26 is to close the parallel-connecting switch 11, thereby connecting the armatures 37 and 38 of the motors 25 and 26, respectively, in parallel relation with the armatures 33 to 36, inclusive, of the 35 corresponding motors 21 to 24, inclusive. A portion of the accelerating resistor 18 is connected in series relation with the armatures 37 and 38 of the motors 25 and 26, respectively, to prevent a heavy surge of electrical energy through the armatures 37 and 40 38 prior to their rotation. Fig. 7 of the drawing which corresponds to position 7 of the sequence chart of Fig. 2, illustrates the parallel circuits which have just been described.

45 The next step in the acceleration of the motors 25 and 26 is to close the switches 9 and 10, in the order illustrated by positions 8 and 9 of the sequence chart of Fig. 2 thereby shunting all of the accelerating resistor 18 that is connected in series relation with the motors 25 and 26.

50 Upon the closure of the switches 9 and 10, the voltage across the terminals of the armatures 37 and 38 of the motors 25 and 26, respectively, is double that of the armatures 33 to 36, inclusive, of the corresponding motors 21 to 24, because there are two armatures connected in series relation in one circuit and four armatures are connected in 55 series relation in the other circuit and the voltage of each circuit is the same.

60 With the energization the same in all of the field magnet windings 27 to 32, inclusive, of the corresponding motors 21 to 26, inclu-

sive, and with the voltage across the terminals of each of the armatures 37 and 38 of the motors 25 and 26, respectively, double that of the voltage across the terminals of each of the armatures 33 to 36, inclusive, of the corresponding motors 21 to 24, inclusive, the speed of the motors 25 and 26 will be approximately double that of the motors 21 to 24, inclusive.

65 With the speed of the armatures 37 and 38 of the motors 25 and 26, respectively, double that of the armatures 33 to 36, inclusive, of the corresponding motors 21 to 24, inclusive, the peripheral speed of the gear wheel 46 will be substantially the same as the peripheral speed of the flanges of the wheel 41 because the gear reduction between the motors 25 and 26 and the gear wheel 46 is approximately double that of the reduction between the motors 21 to 24, inclusive, and the vehicle wheels 46. By having the speed of the motors 25 and 26 double that of the motors 21 to 24, inclusive, it is possible for the motors 25 and 26 to supply as much mechanical energy in the 70 driving of the vehicle as the motors 21 to 24, inclusive, supply. In other words, the tractive effort is distributed equally between the wheels 41 and the gear wheel 46 to 75 supply as much mechanical energy in the driving of the vehicle as the motors 21 to 24, inclusive, supply. In other words, the tractive effort is distributed equally between the wheels 41 and the gear wheel 46 to 80 supply as much mechanical energy in the driving of the vehicle as the motors 21 to 24, inclusive, supply. In other words, the tractive effort is distributed equally between the wheels 41 and the gear wheel 46 to 85 supply as much mechanical energy in the driving of the vehicle as the motors 21 to 24, inclusive, supply. In other words, the tractive effort is distributed equally between the wheels 41 and the gear wheel 46 to 90 supply as much mechanical energy in the driving of the vehicle as the motors 21 to 24, inclusive, supply. In other words, the tractive effort is distributed equally between the wheels 41 and the gear wheel 46 to 95 supply as much mechanical energy in the driving of the vehicle as the motors 21 to 24, inclusive, supply. In other words, the tractive effort is distributed equally between the wheels 41 and the gear wheel 46 to 100 supply as much mechanical energy in the driving of the vehicle as the motors 21 to 24, inclusive, supply. In other words, the tractive effort is distributed equally between the wheels 41 and the gear wheel 46 to 105 supply as much mechanical energy in the driving of the vehicle as the motors 21 to 24, inclusive, supply. In other words, the tractive effort is distributed equally between the wheels 41 and the gear wheel 46 to 110 supply as much mechanical energy in the driving of the vehicle as the motors 21 to 24, inclusive, supply. In other words, the tractive effort is distributed equally between the wheels 41 and the gear wheel 46 to 115 supply as much mechanical energy in the driving of the vehicle as the motors 21 to 24, inclusive, supply. In other words, the tractive effort is distributed equally between the wheels 41 and the gear wheel 46 to 120 supply as much mechanical energy in the driving of the vehicle as the motors 21 to 24, inclusive, supply. In other words, the tractive effort is distributed equally between the wheels 41 and the gear wheel 46 to 125 supply as much mechanical energy in the driving of the vehicle as the motors 21 to 24, inclusive, supply. In other words, the tractive effort is distributed equally between the wheels 41 and the gear wheel 46 to 130 supply as much mechanical energy in the driving of the vehicle as the motors 21 to 24, inclusive, supply. In other words, the tractive effort is distributed equally between the wheels 41 and the gear wheel 46 to

10 At this stage in the operation of the motors 21 to 26, inclusive, the operator permits the locomotive vehicle to travel forward until the gear wheel 46 engages the rack member 48. As the peripheral speed of the gear wheel 46 is substantially the same as the peripheral speed of the flanges of the wheels 41, there is no excessive horizontal thrust upon the teeth of the rack member 48. When the rack wheel 46 has 105 engaged the rack member 48, the necessity for maintaining the peripheral speed of the gear wheel 46 and the wheels 41 precisely the same is eliminated, as they are no longer subject to the shock of engagement.

110 The next step in the acceleration of the motors is to close switches 14, 15, and line switch 17, and open switches 11, 12, and 13, in accordance with position 10 of the sequence chart of Fig. 2. The motors 25 and 26 are now connected in parallel relation to the motors 21 to 24, inclusive, between the source of electrical energy marked "Trolley" and "Ground". That portion of the resistor 18 that remains in series relation with the motors 25 and 26 is substantially equal in electrical resistance value to that portion of the resistor 19 that remains in series relation with the motors 21 to 24, inclusive. The group of motors 21 to 24, inclusive, and the group of motors 25 and 26 are accelerated uniformly by simultaneously closing switches 8 and 3 in accordance with step 11 of the sequence chart of Figure 2, thereby shunting substantially equal portions of the resistors

18 and 19 respectively. The switches 4 and 7 are next closed simultaneously to shunt equal portions of the resistors 18 and 19, this corresponds with step 12 of the sequence 5 chart of Fig. 2 of the drawings.

Lastly, the switches 5 and 6 are closed simultaneously in accordance with step 13 of the sequence chart of Fig. 2, thereby completely shunting all of the resistors 18 and 10 19 and establishing the circuits illustrated by Figure 8 of the drawing. The one circuit, which is established, extends from the source of electrical energy marked "Trolley" through line switch 17, accelerating switches 15 6 to 10, inclusive, armatures 37 and 38 and series field-magnet windings 31 and 32 of the motors 25 and 26, respectively, and ground switch 15 to ground. The other circuit 20 extends from a source of electrical energy marked "Trolley" through the line switch 16, accelerating switches 1 to 5, inclusive, armatures 33 to 36, inclusive, of the corresponding motors 21 to 24, inclusive, switch 14, and series field magnet windings 25 27 to 30, inclusive, of the motors 21 to 24, inclusive, to ground.

From the above description, it is apparent that I have provided means whereby it is possible to bring a motor vehicle upon a portion of railway track in which a rack member is securely fastened, to engage a gear wheel which is mounted upon the locomotive, without injuring the gear wheel or the rack member by the shock of their engagement. I have also provided means for so controlling the energization of the windings and armatures of a plurality of motors employed to drive the motor vehicle that more power is supplied by certain of the motors than by others, and the speed of the motors is maintained at a predetermined ratio to effect desirable operation of the locomotive when operating upon tracks of extremely heavy grade.

45 While I have illustrated my invention in its preferred form, it is apparent that minor modifications may be made in the arrangements of circuits and apparatus employed without departing from the spirit of my invention. I desire, therefore, to be limited only by a scope of appended claims.

I claim:

1. In a motor control system, the combination with a plurality of dynamo-electric machines, of a mechanical load driven by said machines, means for mechanically connecting said machines to said load whereby certain of said machines perform more work than others, and means for energizing each of said machines proportionally to its predetermined share of said mechanical load.

2. In a motor vehicle, the combination with a vehicle having a plurality of wheels, of a motor for driving said wheels, means for mechanically connecting said wheels to said

motor, an additional wheel mounted on said vehicle, a second motor, and means for mechanically connecting said additional wheel to said motor, said second mechanical means differing from said first mechanical means whereby said motors must travel at different speeds to maintain the peripheral speed of said wheels equal, and means for energizing said motors to maintain equal peripheral speed for all of said wheels. 70 75

3. In a motor vehicle, the combination with a vehicle having a plurality of wheels, of a motor for driving said wheels, means for mechanically connecting said motor to said wheels, a gear wheel mounted upon said vehicle for actuating said vehicle on heavy grades, a second motor for driving said gear wheel during abnormal operations, means for mechanically connecting said second motor to said gear wheel and means for energizing said motors to maintain the peripheral speed of said wheels and said gear wheel equal until said gear wheel actuates said vehicle. 80 85

4. In a motor control system, the combination with a vehicle having a plurality of wheels, of a motor for driving said wheels, means for mechanically connecting said motor to said wheels, a gear wheel mounted upon said vehicle, a second motor for driving said gear wheel during abnormal operations, means comprising a gear member for mechanically connecting said second motor to said gear wheel, said mechanical means being so constructed that the speed of said first and second motor must differ for the peripheral speed of said gear wheel to equal the peripheral speed of said wheels and means for energizing said motors to maintain the peripheral speed of said wheels and 105 said gear wheel substantially equal during a predetermined time. 100 105

5. In a control system, the combination with a plurality of dynamo-electric machines, each of said machines having an armature and a field-magnet winding, of means for connecting said windings of said machines in series relation one with the other, means for connecting in unequal groups certain of said armatures of said machines in series relation one with the other, and means for connecting said unequal groups of armatures in parallel relation one to the other. 110 115

6. In a control system, the combination with a plurality of dynamo-electric machines, each of said machines having an armature and a field-magnet winding, of means for connecting said windings of said machines in series relation one with the other, means for connecting in unequal groups certain of said armatures of said machines in series relation one with the other, one of said groups having double the 120 125 130 number of armatures of the other group,

and means for connecting said unequal groups of armatures in parallel relation one to the other.

7. In a control system, the combination 5 with a plurality of dynamo-electric machines, each of said machines having an armature and a field-magnet winding, of a plurality of switches for connecting the field-magnet windings of all of said machines in series relation with the armatures 10 of certain of said machines, said armatures constituting a group, a switch for connecting in a second group, others of said armatures in series relation one with another and 15 in parallel relation with said first group of armatures and means for making the voltage across one group of armatures the same as across another group of armatures.

8. In a control system, the combination 20 with a plurality of motors, each of said motors having an armature and a field magnet winding, of a resistor, a switch for connecting the armatures and field-magnet windings of four of said motors in series relation 25 one with another and with said resistor, two switches for connecting the field-magnet windings of two of said motors in series relation with said four motors and said resistor, a parallel-connecting switch and a 30 second resistor for connecting the armatures of said two motors in parallel relation to said armatures of said four motors, a source of electrical energy, a line switch for con-

necting said four motors to said source of energy and a second line switch for connecting said second resistor directly to said source of electrical energy and independent of said parallel-connecting switch. 35

9. The method of energizing a plurality of motors, each having an armature and a field-magnet winding that comprises connecting certain of said motors in series relation one with another, then inserting the field-magnet windings of other of said motors in series relation with said series connected 40 motors and then connecting the armatures of said other motors in series relation one with another and in parallel relation with armatures of said series connected 45 motors. 50

10. The method of energizing a plurality of motors, each having an armature and a field-magnet winding whereby a group of said motors are energized to rotate their respective armatures at a predetermined 55 speed, the remaining motors next having their field-magnet windings energized to the same value as the field magnet windings of said group of motors, and then energizing the armatures of said remaining motors to 60 double the value of the energization of each armature of said first group.

In testimony whereof, I have hereunto subscribed my name this 7th day of October, 1924.

ELDEN I. STAPLES.
